IGNITION APPARATUS

James L. Arthur, Ind., assignor, by
mesne assignments, to General Motors Corporation, Detroit, Mich., a corporation of Delaware

Application December 30, 1931, Serial No. 583,909

4 Claims. (CL 123—117)

This invention relates to ignition apparatus for internal combustion engines and particularly to engine suction control devices for controlling the timing of the ignition.

It is an object of the present invention to provide for positively retarding the ignition while the engine is idling, while providing for the automatic advancing of the ignition when the throttle is opened to increase the speed of the engine. In order to accomplish this object I provide means responsive to engine suction for retarding the spark while the engine is idling. I preferably connect the suction chamber of said means with a port in the intake manifold near the edge of the throttle, when closed, and on the engine side of the throttle. When the throttle is opened to cause the engine speed to increase substantially above idling speed, the suction at this port is insufficient to hold the spark timer in fully retarded position. Centrifugal means is provided for advancing the spark as the engine speed increases.

Further objects and advantages of the present invention will be apparent from the following description, reference being had to the accompanying drawings wherein a preferred embodiment of one form of the present invention is clearly shown.

In the drawings:

Fig. 1 is a diagram of the embodiment of the present invention, a portion of the apparatus being shown in section, the section being taken on the line 1—1 of Fig. 4.

Figs. 2 and 3 are charts showing the operation of the device.

Fig. 4 is a fragmentary view partly in longitudinal section of an ignition timer equipped with a form of the present invention.

Fig. 5 is a sectional view on the line 5—5 of Fig. 4.

Fig. 6 is a sectional view on line 6—6 of Fig. 4.

Referring to Fig. 4, 20 designates an ignition timer housing provided with a shank 21 having a bearing portion 22 received by the well in an engine frame, a fragment of which is indicated at 23. The shank 21 provides a bearing for a shaft 24 driven by the engine in any suitable manner. Shaft 24 drives a weight plate 25 carrying studs 26 upon which are pivotally mounted weights 27 having arms 28 bearing against arms 29 attached to a sleeve 30, which provides a cam 31. The arms 27 are urged toward the shaft 24 by springs 32 attached to studs 26 and to studs 33 carried by the arms 29. Cam 31 drives a distributor rotor 34 carrying a segment

35 which moves past distributor posts 36 carried by a head 37. The segment 35 is connected to a spring conductor 38 bearing against a center button 39.

Referring to Fig. 1, the cam 31 operates upon a rubbing block 40 attached to a circuit breaker lever 41 carrying a contact 42 which cooperates with a grounded contact 43. The rubbing block 40 is urged toward the cam 31 by a leaf spring conductor 44 attached at one end to an insulating terminal 45 and at the other end of the lever 41. In the example given, the direction of rotation of the cam 31 is clockwise as indicated by arrow 46. What has been described thus far is a conventional form of ignition timer 18 to which the present invention can be applied as an attachment.

Screws 50a secure to the engine frame 23 shown in Fig. 1 a bracket 50 to which nuts 51 and studs 52 attach a housing 53 having a flange 54 bent over the periphery of a housing 55 in order to secure at its edge a flexible diaphragm 56 which may be made of thin flexible metal or from a plurality of layers of varnished aero plane linen or similar material. The housing 55 carries an internally threaded bushing 57 into which is secured a cap 58 to which is secured a connection 59 for a pipe 60 attached by connection 61 to a threaded opening 62 in a carburetor frame 63. The opening 62 communicates with a port 64 drilled through the carburetor frame, which port is at a point near the edge of the throttle valve 65 so that when the valve is in the closed or in idle position the port will be on the engine side of the valve 65 and so that when the valve is opened to any point beyond idling or low engine speeds the port will be on the carburetor side of the valve. The valve 65 is mounted on a shaft 66 which is operated in any suitable manner. The cap 58 provides a seat for a spring 70 which surrounds sleeve 71 and which is seated at its left hand end in a flange 72 provided by the sleeve 71. The spring 70 therefore urges the sleeve 71 against a washer 73 secured to the diaphragm 56 together with another washer 74 by riveting over the shank 75 of a rod 76. The rod 76 passes through an opening surrounded by a flange 77 provided by the housing 53 and through an opening 78 provided in the bracket 50. The rod 76 is attached by a wire 79 to a stud 80 through which the wire passes and to which the wire is secured by a screw 81. The stud 80 is swivelly connected with a clamping bracket 82 which is provided with clamping arms 83 which are forced into

clamping engagement with the shank portion 22 of housing 20 by a screw 84 and cooperating nut 85. The clamp arm 82 rests upon an upper surface of the well portion 23 of the engine frame and is held down resiliently by a spring 90 pressing downwardly upon washer 91 resting upon the plate 82 and pressing upwardly against the head of a screw 92 which passes through an arcuate slot 93 in the plate 82 and is received 10 by tapped hole in the well portion 23.

Referring to Fig. 2, curve a—b—c—d shows the vacuum in inches of mercury at the port 64 for various engine speeds when the engine is operating to produce sufficient torque to drive the 15 vehicle along a level road. It will be noted that when the engine is idling, that is running between a speed corresponding to a vehicle speed from about 2 to 10 miles per hour the vacuum at the port 64 is relatively high and will be 20 sufficient to overcome the spring 70 to advance the ignition and to move the diaphragm 56 toward the right to retard the ignition. As the speed of the engine is increased above 10 miles per hour in response to opening the throttle 25 65, the vacuum at the port 64 decreases very rapidly as indicated by curve b—c showing the vacuum at a speed between 10 and 30 miles per hour under road torque operating conditions. Curve c—d indicates that above 30 miles per 30 hour the vacuum increases due to the increase in speed.

Referring to Fig. 3, the curve e—f—g—h—k represents the spark advance curve for an ignition timer controlled by combined centrifugal 35 means and suction means. The centrifugal advance may be constructed so that it will start to advance the spark at 15 miles per hour from an initial advance of 5°. The centrifugal device advances the spark in the manner represented 40 by the line h—k.

The curve a—b—c—d shows the vacuum in inches of mercury at the port 64 as the throttle valve 65 is opened to cause the engine to operate to increase the speed of the vehicle when driving over a level road. It will be noted that as the throttle 65 is opened to increase the speed from about 2 to 10 miles per hour, the vacuum at the port 64 increases rapidly from about 10 inches of mercury indicated at A to about 17 45 indicated at point B. The spring 70 is overcome when the suction in inches of mercury exceeds 10 inches and the diaphragm 56 moves toward the right to retard the ignition from about +5° to about -10° as indicated by line 50 e—f in Fig. 3. When the throttle is opened still wider to cause the engine to drive the vehicle about 15 miles per hour, the vacuum falls off rapidly at the port 64. Hence, the spring 70 operates to advance the ignition as indicated by 55 the line g—h. The flat portion f—g of curve e—f—g—h is due to the fact that when the vacuum is at port 64 above approximately 14 inches of mercury, the tube 71 will be drawn the full distance toward the right wherein the tube 60 71 engages the cap 58 thereby preventing further retarding of the spark although the vacuum may increase substantially above 14 inches of mercury. At speeds above approximately 15 65 miles per hour as indicated by c—d in Fig. 2, the 70 vacuum is insufficient to overcome the spring 70 which maintains the plate 82 in its maximum advance position. Therefore at speeds above 15 miles per hour the centrifugal device controls the advancing of the ignition as indicated by 75 line h—k which represents the centrifugal ad-

vance under full load operating conditions. The dotted line e—h represents the fact that the advance is never less than 5° under full load operating conditions.

Thus there has been provided a control for 5 ignition apparatus by which, when the vehicle speed is below a certain value, such as when the engine is idling, the ignition timing is controlled by engine suction only to retard the spark. Above a certain engine speed the suction device 10 is inoperative to retard the ignition and the control of ignition timing is effected solely by a centrifugal device.

The suction device therefore does automatically which heretofore might have been done 15 manually with respect to an ignition apparatus having combined manual control and centrifugal control. It is well known that an internal combustion engine will idle better when the spark is retarded, but automobile drivers seldom remember to retard the spark when idling. The result is, that due to slight unevenness of engine speed while idling with advanced spark, the engine may tend to stall. The possibility of stalling is increased by the advent of "free 25 wheeling" in automobiles. The present invention therefore reduces the possibility of engine stalling since the spark is automatically retarded in response to engine idling conditions.

While the form of embodiment of the present 30 invention as herein disclosed constitutes a preferred form, it is to be understood that other forms might be adopted, all coming within the scope of the claims which follow.

What is claimed is as follows:

1. Ignition control apparatus for internal combustion engines having a fuel pipe through which a fuel charge is drawn to the engine cylinders comprising, in combination, a circuit breaker, a cam for operating the breaker, and 40 means for effecting a relative angular adjustment between the cam and circuit breaker in a direction to retard the spark timing while the engine is idling and in response to engine produced suction in the engine fuel pipe, said means 45 including a suction chamber, a displacement member in said chamber, and a pipe connecting said chamber with the fuel pipe of the engine only at a point adjacent the edge of the engine throttle valve when closed and on the engine 50 side of said valve.

2. Ignition apparatus for internal combustion engines comprising, in combination, a circuit breaker, a cam for operating the breaker, a suction chamber connected with the fuel pipe of 55 the engine only at a point adjacent the edge of the engine throttle valve when closed and on the engine side of said valve, a displacement member in said chamber, and means for connecting the displacement member with the circuit breaker in order to vary the angular relation between the circuit breaker and cam in a direction to retard the spark timing while the engine is idling.

3. A spark timing control for internal combustion engines, wherein a charge of fuel is drawn into the engine cylinders through the fuel pipe whereupon an angularly adjustable ignition timer becomes effective to cause the firing of the fuel charge, comprising in combination, the combination with said ignition timer of means for effecting relative angular adjustment of the ignition timer in a direction to retard the spark timing while the engine is idling and in response to engine produced suction in the engine fuel pipe, said means including a suc- 65 70 75 76

tion chamber, a displacement member in said chamber, and a pipe connecting said chamber with the fuel pipe of the engine only at a point adjacent the edge of the engine throttle valve when closed and on the engine side of said valve.

4. A spark timing control for internal combustion engines, wherein a fuel pipe supplies a fuel mixture drawn into the engine cylinders under reduced pressure to be ignited, comprising in combination, a circuit breaker, a cam for operating the breaker, and means for effecting a

relative angular adjustment between the cam and circuit breaker in a direction to retard the spark timing while the engine is idling and in response to engine produced suction in the engine fuel pipe, said means including a suction chamber, a displacement member in said chamber, and a pipe connecting said chamber with the fuel pipe of the engine only at a point adjacent the edge of the engine throttle valve when closed and on the engine side of said valve. 10
